REFRIGERATING APPARATUS

Wynne G. Winkler, Dayton, Ohio, assignor to
General Motors Corporation, Dayton, Ohio, a
corporation of Delaware

Application November 13, 1937, Serial No. 174,287

9 Claims. (Cl. 225—40)

This invention relates to refrigeration and particularly to the cooling of beverages within containers.

An object of my invention is to provide an improved system of cooling and dispensing a beverage such as beer or the like from containers.

Another object of my invention is to provide an improved beer container, keg or barrel having a cooling fluid coil disposed therein and constructed so as to facilitate the act of connecting same into or disconnecting same from a cooling and dispensing system.

A further object of my invention is to provide a beer keg or barrel having a cooling fluid coil normally disposed therein during transportation of the beer barrel and which coil can be readily removed from the keg or barrel to permit thorough cleaning thereof in the conventional brewery barrel or keg rotating and whirling washing machines.

A still further object of my invention is to provide a beer keg or barrel with a removable head portion which carries valved tap or pipe connections and also has a cooling fluid coil secured thereto so as to be removable as a unit from the keg or barrel along with the removable head portion thereof.

In carrying out the preceding objects it is a further and more specific object of my invention to provide a beer keg or barrel with a removable head carrying integrally therewith valved tap or pipe connections and a cooling fluid coil which extends from the head a substantial distance into the keg or barrel and is of such shape or arrangement as to spread same over a large area within the keg or barrel to uniformly and more efficiently cool beer therein.

Further objects and advantages of the present invention will be apparent from the following description, reference being had to the accompanying drawings, wherein a preferred form of the present invention is clearly shown.

In the drawings:

Fig. 1 is a diagrammatic showing of a cooling and dispensing system having containers constructed in accordance with my invention located therein;

Fig. 2 is a fragmentary enlarged vertical sectional view through one of the beer kegs or barrels of the system shown in Fig. 1 and disclosing a removable head having integral valved tap or pipe connections and carrying a cooling fluid coil;

Fig. 3 is a view of a tap means secured to the removable head portion of the keg or barrel;

Fig. 4 is a perspective view of a fitting adapted

to be attached to the tap means shown in Fig. 3;

Fig. 5 is an enlarged sectional view of a valved pipe connection device carried by the removable head portion of a keg or barrel; and

Fig. 6 is a view of a key joint or connector adapted to be attached to the device shown in Fig. 5.

Referring to the drawings, for illustrating the present invention, I have shown in Fig. 1 thereof a beer cooling and dispensing system which includes a central cooling apparatus comprising an insulated liquid compartment or tank 10 having a cooling element or evaporator 11 of a closed refrigerating system disposed therein. The closed refrigerating system includes a compressor 12 connected to evaporator 11 by a conduit 14 and having another connection 15 with a condenser 16. Motor 17 drives the compressor 12, through suitable belt and pulley connections, and is controlled by a switch 18 operated in response to the expansion and contraction of a bellows 21 connected to a thermostat 22 located within the liquid container or tank 10 in the usual and well-known manner. Evaporated or gaseous refrigerant withdrawn from evaporator 11 by compressor 12, through conduit 14, is compressed and forwarded under pressure through conduit 15 to the condenser 16. The compressed refrigerant is cooled and liquified in condenser 16 and flows into a receiver 24. Liquid refrigerant flows to evaporator 11, through a conduit 25, under the control of an expansion device or valve 26 which is opened and closed by a thermostat 27 in response to the temperature of refrigerant within the outlet end of the evaporator coil 11. The thermostat 22 controls operations of motor 17 and consequently compressor 12 to maintain the cooling fluid or liquid in tank 10 between predetermined temperature limits.

The system shown in Fig. 1 also includes a plurality of kegs or barrels 31 each having a coil 32 disposed therein. One end of each coil 32 has a pipe connection 33 with a cooling liquid distributing pipe 34 which communicates with a pump 35. Pump 35 communicates, through pipe 36, with the cooling liquid contained in tank 10 and when operated by a motor 37 forces the cooling liquid from tank 10 into and through the coils 32. The opposite end of each coil 32 communicates, through a pipe 38, with a conduit 41 which opens into the top of tank 10 and serves to return the cooling liquid circulated through coils 32 to the reservoir or tank 10. Each keg or barrel 31 has a combined tap faucet and foam controlling device, generally represented by the

reference character 43, extending upwardly therefrom and communicating with the interior of the barrel for dispensing beer therefrom. Each keg or barrel 31 also has a pipe line 44 communicating with the interior thereof through a valved joint, generally represented by the reference character 45, to be hereinafter more fully described. The pipe line 44 has suitable manually actuated shut-off valves 46 and a combined automatic regulating valve and indicating device 47 interposed therein. Pipe line 44 is connected, through device 47, with a drum or tank 48 containing carbon dioxide under pressure. The combined regulating and indicating device 47 automatically maintains the beer within the kegs or barrels 31 at a predetermined desired pressure by continuously or intermittently admitting carbon dioxide into the kegs or barrels by way of pipe line 44. The system shown in Fig. 1 is more or less conventional and well known to those skilled in the art and therefore a more detailed description thereof herein is believed unnecessary.

My invention relates particularly to the construction and arrangement of a beer keg or barrel for installation in a beer cooling and dispensing system such, for example, as the system illustrated in Fig. 1 whereby certain new results and advantages are obtained. Referring now to Fig. 2 of the drawings, I have shown the end 51 of one of the wood beer kegs or barrels 31 cut out as at 52 to provide a relatively large opening 53 in the end of the barrel. A metal ring 54, preferably split at one or more points to permit same to be inserted through the opening 53, is secured to the keg or barrel end 51 by a plurality of screws or the like 55. The ring 54 provides a mounting for a metal closure plate 56 of circular contour having a plurality of elements, to be presently described, secured thereto. A rubber, or the like, resilient gasket 57 is located between the plate 56 and the end 51 of keg or barrel 31 to seal the contents of the keg or barrel therein when bolts 58 are passed through the end wall 51 and threaded into the mounting ring 54. The cooling fluid coil 32 located within keg or barrel 31 is mounted upon plate 56 by having its ends 61 and 62 which extend through the closure plate or head 56 welded or otherwise secured thereto. The combined foam controlling and tap or faucet device 43 includes a metal member 64 (see Fig. 2) having a shank portion 65 welded or otherwise permanently secured to and extending through the plate 56. Member 64 forms a rigid integral part of the plate or head 56 for mounting the device 43 upon the keg or barrel 31. This member 64 has a cone-shaped valve seat 66 formed therein and adapted to receive a cone-shaped sealing surface 67 provided on a valve 68. Valve 68 is enlarged at its upper end and threaded as at 69 upon an enlarged threaded opening 71 formed in member 64. The enlarged upper end of valve 68 is provided with several small openings 72 which serve to permit beer to flow through the valve to device 43 when the valve surface 67 is moved from its seat 66 in a manner to be hereinafter described. The member 64 has an enlarged outwardly extending peripheral portion 74 provided with shoulders 75 and 76 (see Fig. 3). The portion 74 and shoulders 75 and 76 of member 64 form a bayonet-like joint for receiving a removable collar-like part 78 (see Fig. 4) of the joint. The collar-like part 78 of the joint shown in Fig. 2 is provided with a pair of inwardly projecting lugs 79 which are adapted to slip through a pair of oppositely disposed and verti-

cally extending slots 81 provided in the enlarged portion 74 of member 64. When collar 78 shown in Fig. 4 is placed on member 64 it is rotated a quarter turn so as to cause the lugs 79 to fit under and engage the shoulder 75 provided on the member 64 to thus lock the two parts 64 and 78 of the bayonet-like joint tightly together. Collar 78 has its outer surface threaded as at 83 for receiving a threaded wing nut 84 (see Fig. 2). This nut 84 has an inwardly directed flanged portion 85 which clamps a flange 86, formed on a housing 87 of device 43, to member 64 with a gasket 88 therebetween. The housing 87 of device 43 has a horizontally extending outlet 89 at the top thereof connected to a faucet 91. Housing 87 is also provided with an opening in its top wall through which a valve stem 92 extends. Stem 92 is provided with a knurled head 93 at its outer end and a squared or the like key portion 94 at its inner end. The opening in housing 87 through which the stem 92 extends is sealed by a packing gland 95 and a nut 96. The squared or the like keg portion 94 of stem 92 fits into a similarly shaped opening 97 provided in valve 68 and, upon rotation of stem 92, for a purpose to be hereinafter described, adjusts the valve 68 relative to its seat 66. A tap pipe 98 is welded or otherwise secured to the metal member 64 and extends downwardly into the keg or barrel 31 to a point adjacent the bottom thereof and serves as an outlet conduit for the egress of beer from the keg or barrel through head 56 to the device 43.

The valved joint or pipe connection 45 communicating with the interior of keg or barrel 31 through closure plate 56 includes a valve housing 101 welded or otherwise permanently secured to plate 56. Housing 101 contains a valve 102 which has a vertical opening 103 and a registering horizontal opening 104 extending therethrough (see Fig. 5). Valve 102 has an integral stem 105 extending below housing 101, and a spring 106 surrounding this stem is compressed and secured in place by a washer 107 which holds the valve 102 against its seat 108 provided in the housing. The housing 101 is provided with a horizontal hole 109 located below plate 56 and disposed on the same plane with opening 104 in valve 102 so as to register therewith upon rotation of the valve. The upper end of housing 101 is hollowed out as at 110 and provided with an inwardly directed flange 112 which forms the stationary part of the bayonet-like valved joint 45. Valve 102 also has a key slot 114 cut in its top surface for receiving a portion of a male member of the joint. This male member of the joint comprises two lugs 115 formed on a second valve housing 116 (see Fig. 6). The lugs 115 on housing 116 are adapted to pass through suitable slots 117 provided in the flange 112 on housing 101 so as to fit under the flange 112 and into the key slot 114 provided in valve 102. Thus by rotating the housing 116, shown in Fig. 6, a quarter turn lugs 115 lock housing 116 upon housing 101 with a gasket 118 therebetween to seal the two portions of the valved bayonet pipe joint 45 together. This rotation of housing 116 also moves the valve 102 into a position whereby the hole 104 therein registers with the hole 109 in housing 101 to open the passage through the normally closed joint 45. Housing 116 contains a ball check valve 121 (see Fig. 1) normally forced against its seat 122 by a spring 123 bearing against a washer 124. The check valve 121 is located in a passage 125 extending through housing 116 and connected to the pipe 75

line 44 to prevent release of pressure from keg or barrel 31.

In providing the structure above described, the use of new or specially constructed barrels or kegs is unnecessary since the present day wooden kegs or barrels are merely modified to accommodate the improved structure of the present invention by cutting the hole 53 in an end thereof. The closure plate or head 56, coil 32, tap pipe 98, member 64 and the valve 68 therein, together with housing 101 and valve 102 disposed therein are all secured together and secured to keg or barrel 31 as a unitary structure and transported to and from the brewery as a unit. When this unit is received at the brewery, the closure plate or head 56 and the elements secured thereto are removed from the keg or barrel 31 by removing the bolts 58. The removal of this unit permits the beer barrel or keg to be rotated and whirled in the conventional brewery barrel washing machines to thoroughly clean the barrel or keg. The unitary barrel sealing structure, comprising the head or plate 56, coil 32, pipe 98, member 64 and the valve 68 therein together with the housing 101 and valve 102 therein, is replaced upon the keg or barrel prior to filling same. The valve 68 within member 64 and the valve 102 within housing 101 are both normally closed after the barrel or keg 31 has been filled with beer so as to seal the beer within the barrel during transportation thereof to a place, such as the system shown in Fig. 1, for dispensing the beer. At the place of installation of the barrel 31 for dispensing beer therefrom the tap faucet device 43 is first to be attached to the barrel. Therefore, collar 78 is placed over member 64 and rotated so that the lugs 79 thereon lock same to the enlarged head portion 74 of member 64. Thereafter, washer or gasket 88 is placed in position on member 64 beneath the flange 86 on housing 87 of device 43. The wing nut 84 is lowered over flange 86 and tightly threaded upon the threads 83 formed on collar 78 to firmly hold the device 43 upon the keg 31. Valve 68, of course being closed, must now be opened to permit flow of beer through pipe 98 to housing 87 and faucet 91. Therefore, stem 92 is lowered relative to housing 87, by a pushing on the head 93 thereof, and rotated until the squared lower end 94 thereof engages the squared opening 97 in valve 68. With the faucet 91 in closed position, stem 92 is rotated to move valve 68 upwardly within its housing member 64 by movement of threads 69 relative to threads 71. This rotary movement of valve 68 is continued until its cone-shaped sealing surface 67 has moved a predetermined desired distance away from the cone-shaped valve seat 66. Opening of valve 68 thereby permits beer to flow from keg or barrel 31 through the stationary tap pipe 98 and into housing 87 of device 43 to the dispensing faucet 91.

After assembling the device 43 upon the keg or barrel 31 and preparatory to dispensing beer from the barrel, the valved joint 45, connected with the carbon dioxide pipe line 44, must be attached to the barrel. To connect the one portion of the joint 45 with the other portion thereof and to simultaneously open the passage through valve 102, the lugs 115 on housing 116 are inserted into the open end 111 of housing 101. The lugs 115 enter the key slot 114 provided in valve 102 and the housing 116 is rotated a quarter turn to cause the lugs to tightly engage the flange 112 and lock housing 116 upon housing 101. This rotation of housing 116 and lugs 115 simultaneously opens

valve 102 or, in other words, rotates opening 104 into registration with opening 109 to cause communication of the passage 125 through the valved device 45 with keg 31. The pipes 33 and 39 of the liquid cooling circuit are then connected to the ends 62 and 61 respectively of the cooling fluid coil 32 located within the keg or barrel 31. The liquid contained in the insulated reservoir or tank 10 of the system shown in Fig. 1 and cooled by the evaporator 11 of the refrigerating system is circulated by pump 35, by way of pipes 34 and 33, to the coil 32 to cool the beer in the keg or barrel 31. The cooling liquid passes through coil 32 into pipes 39 and 41 from where it flows into the tank 10 and dissipates heat, absorbed from the beer, to the evaporator 11. Valve 46 in pipe line 44, communicating with the valved device 45, is opened to permit carbon dioxide to flow from the container 48 and line 44 into the barrel 31 until a pressure, predetermined by the automatic regulating valve 47, has been attained in the barrel. The beer upon being brought to the desired pressure and temperature is now ready to be dispensed through faucet 91. Should the beer foam too much or, on the other hand, not enough stem 92 is rotated to adjust valve 68 relative to its seat 66 to thereby cause the beer to create a desired amount of foam. Thus the valve 68 serves a two-fold purpose since it is the device for tapping the barrel of beer and is also utilized as a foam control device. When the beer barrel is emptied, the dispensing device 43 and the one part 116 of valved joint 45 are removed from the keg or barrel and the pipe lines 33, 39 and 44 are closed. The keg or barrel containing the unit comprising plate or head 56, coil 32, pipe 98, member 64 and valve 68 therein together with housing 101 and the valve 102 disposed therein is again transported to the brewery where the units comprising the elements described and particularly the cooling coil 32 may be bodily removed from the keg or barrel.

From the foregoing, it will be seen that I have provided an improvement in the construction and arrangement of unitary removable tapping and dispensing structures for beer kegs or barrels. By providing a beer barrel with a unitary removable structure comprising a head having integrally formed therewith a tap device, a cooling fluid coil and a pressure maintaining connection, the operation of tapping into the keg or barrel and installing same in a beer cooling and dispensing system is greatly facilitated.

My improved removable unitary structure also permits thorough cleaning of the beer keg or barrel without danger of damaging parts thereof which are to be transported along with the keg or barrel after same has been filled with beer. Furthermore, my improved structure permits spreading of the cooling fluid coil over a large portion of the interior of a keg or barrel to thereby uniformly and more efficiently cool the beer therein.

While the form of embodiment of the invention as herein disclosed, constitutes a preferred form, it is to be understood that other forms might be adopted, all coming within the scope of the claims which follow.

What is claimed is as follows:

1. In combination with a beer barrel having an opening at one end thereof, a structure including a head plate removably secured to said barrel and normally closing the opening at said end thereof, said head plate having a plurality of normally closed fluid pipe connections provided

- therein and adapted to communicate with the interior of said barrel, conduit means secured to said head plate and extending therefrom a substantial distance into said barrel, said conduit means having its ends opening exteriorly of said barrel for connection with a cooling fluid circulating system, and said plurality of pipe connections and said conduit means being removable as a unit from said barrel with said head plate.
5. In combination with a beer barrel having an opening at one end thereof, a structure including a head plate removably secured to said barrel and normally closing the opening at said end thereof, said head plate having a plurality of normally closed fluid pipe connections provided therein and adapted to communicate with the interior of said barrel, conduit means secured to said head plate and extending therefrom a substantial distance into said barrel, said conduit means having its ends opening exteriorly of said barrel for connection with a cooling fluid circulating system, one of said fluid pipe connections having a valve therein and providing an outlet for the flow of beer from said barrel, and said valve being adjustable to control the flow of beer from said barrel, and said plurality of pipe connections and said conduit means being removable as a unit from said barrel with said head plate.
10. In combination with a beer barrel having an opening at one end thereof, a structure including a head plate removably secured to said barrel and normally closing the opening at said end thereof, said head plate having a plurality of separate spaced apart normally closed fluid pipe connections provided therein and adapted to communicate with the interior of said barrel, a pipe coil secured to said head plate and extending therefrom a substantial distance into said barrel, said coil having its convolutions widely spread apart to extend the coil throughout the major portion of the height of the barrel, said coil having its ends opening exteriorly of said barrel for connection with a cooling fluid circulating system, and said plurality of pipe connections and said coil being removable as a unit from said barrel with said head plate.
15. In combination with a beer barrel having an opening at one end thereof, a structure including a head plate removably secured to said barrel and normally closing the opening at said end thereof, said head plate having a plurality of separate spaced apart normally closed fluid pipe connections provided therein and adapted to communicate with the interior of said barrel, a pipe coil secured to said head plate and extending therefrom a substantial distance into said barrel, said coil having its convolutions widely spread apart to extend the coil throughout the major portion of the height of the barrel, said coil having its ends opening exteriorly of said barrel for connection with a cooling fluid circulating system, one of said fluid pipe connections having a valve therein and providing an outlet for the flow of beer from said barrel, and said valve being adjustable to control the flow of beer from said barrel, and said plurality of pipe connections and said conduit means being removable as a unit from said barrel with said head plate.
20. A unitary removable dispensing and cooler head for a beer barrel, comprising a plate adapted to close an opening in an end of the barrel, a coil of pipe extending from said plate for insertion into the barrel, a plurality of valved pipe connections secured to said plate, and one of said valved connections providing an outlet for the flow of beer through said unitary head.
25. A unitary removable dispensing and cooler head for a beer barrel, comprising a plate of circular contour adapted to close an opening in an end of the barrel, a coil of pipe extending from said plate for insertion into the barrel, said coil of pipe having its ends secured to and extending through said plate, a plurality of valved pipe connections secured to said plate, and one of said valved connections providing an outlet for the flow of beer through said unitary head.
30. A unitary removable dispensing and cooler head for a beer barrel, comprising a plate of circular contour adapted to close an opening in an end of the barrel, a coil of pipe extending from said plate for insertion into the barrel, said coil of pipe having its ends secured to and extending through said plate, the convolutions of said coil of pipe being widely spread apart to extend the coil a substantial distance into a barrel, a plurality of pipe connections secured to said plate, and one of said pipe connections having a normally closed valve therein adapted to be opened to provide an outlet for the flow of beer through said unitary head.
35. A unitary removable dispensing and cooler head for a beer barrel, comprising a plate of circular contour adapted to close an opening in an end of the barrel, a coil of pipe extending from said plate for insertion into the barrel, said coil of pipe having its ends secured to and extending through said plate, a plurality of valved pipe connections secured to said plate, one of said valved pipe connections providing an outlet for the flow of beer through said unitary head, and the valve in said one of said valved pipe connections being adjustable for controlling said outlet.
40. In combination with a beer barrel having an opening at one end thereof, a structure including a head plate detachably secured to said barrel and normally closing the opening at said end thereof, said head plate having a normally closed fluid pipe connection provided therein and adapted to communicate with the interior of said barrel, conduit means secured to said head plate and extending therefrom a substantial distance into said barrel, said conduit means having its ends sealed to said plate and opening exteriorly of said barrel, said conduit means being adapted to be connected with a cooling fluid system for circulating cooling fluid therethrough and in intimate heat exchange relation with beer in said barrel, and said pipe connection and said conduit means being removable as a unit from said barrel with said head plate.

WYNNE G. WINKLER. 6
